(57) **CLAIM**

I claim the ornamental design for a modular platform for antenna array, as shown and described.

DESCRIPTION

FIG. 1 is a perspective side view of a modular platform for antenna array showing my new, original, and ornamental design;

FIG. 2 is a side view thereof;

FIG. 3 is a top view thereof;

FIG. 4 is a bottom view thereof;

FIG. 5 is a front thereof; and,

FIG. 6 is a rear view thereof.

The broken line showing of certain structures in the drawings is for the purpose of illustrating optional features and forms no part of the claimed design.
